UNITED STATES PATENT OFFICE.

JOSEPH RAYMOND YOUNG, OF MINNEAPOLIS, MINNESOTA.

AUTOMATIC ALIGNING ATTACHMENT FOR MANIFOLDING DEVICES.

Application filed June 30, 1926. Serial No. 119,655.

My invention has for its object to provide in automatic aligning attachment for manifolding devices such as those commercially known as record writing and accounting machines of the type employing the continuous length style of forms, either in rolls or folded, such as invoices, orders, requisitions and the like. These forms may contain two or more webs or strips of paper, depending on the number of copies required, that have longitudinally spaced pairs of aligned holes punched therein in definite arrangement. These webs of paper are fed from the rear to the front of the machine over a flat bed or platen on the writing machine and between carbon sheets. At the front edge of the platen is a co-operating yieldingly held paper clamp that normally holds the free end portions of the first set of forms on the platen while the same is being filled in by the writing machine. Said paper clamp also affords a tearing blade for detaching the sets of forms as they are filled in and drawn from the machine.

The paper clamp is arranged to be released by manually operated foot pedal connections, and the webs are drawn forward over the platen by the operator who grasps the completed set of forms at a point under the released paper clamp, pulls the same forward and then releases said clamp and tears the completed set of forms off along the front longitudinal edges of the paper clamp. This pulling of the webs forward over the platen and tearing the completed sets of forms from the webs at the paper clamp tends to get the forms of the several sets out of perfect registration and alignment. It may be here stated that unless the forms are kept properly aligned both longitudinally and transversely the line spacing and the letter spacing of the carbon copies will not appear in their proper spaces on the copies and hence will not be legible.

Various different devices have been employed to keep the sets of forms in proper alignment, but they have all required extra work on the part of the operator, and most operators try to keep the forms aligned by inserting a pencil or similar instrument into the punched holes.

My invention provides a pair of aligning pins that automatically and successively enter each pair of punched holes in the forms

as they are pulled over the platen by the operator, and thus keep the forms in perfect alignment both longitudinally and transversely.

Said invention further provides automatic means for releasing the aligned pins from the engaged holes at the time the operator manipulates the pedal to release the paper clamp at the completion of the filling in of a set of forms, to release the same so that they may be pulled forward from the machine and torn off at the paper clamp. This pulling of a completed set of forms from the machine is stopped by the pins automatically entering the next set of punched holes which properly positions the completed set of forms in respect to the paper clamp.

The invention further provides other important features, as will hereinafter appear.

In the accompanying drawings, which illustrate the invention, like characters indicate like parts throughout the several views.

Referring to the drawings:

Fig. 1 is a plan view of the invention;

Fig. 2 is a left side elevation of the same;

Fig. 3 is a transverse vertical section taken on the line 3—3 of Fig. 2;

Fig. 4 is a fragmentary plan view of the parts shown in Fig. 3 with some parts indicated by means of broken lines;

Fig. 5 is a detail view principally in section taken on the line 5—5 of Fig. 4;

Fig. 6 is a view corresponding to Fig. 5 but showing certain of the parts in different positions; and

Fig. 7 is a detail view with some parts sectioned on the line 7—7 of Fig. 3.

In the drawings, the invention is shown embodied in an "Elliott-Fisher automatic feed machine", and of the parts thereof it is important to note the frame, comprising a horizontal skeleton top member 8 and laterally spaced leg-equipped side members 9; a horizontal flat bed or platen 10 mounted in the frame member 8 has its front end attached to the frame member 8 by a horizontal hinge joint 11; and a paper clamp 12 transversely overlying the front end portion of the bed 10 for co-operation therewith.

Mounted in the frame member 8 is a pair of transverse rock shafts 13 and 14 and a pair of toggle levers each comprising a short arm 15 and a long arm 16 all rigidly secured

to the shafts 13 and 14, respectively, and connected by a slip joint. The long arms 16 of the toggle levers have short upstanding legs 17 on which the rear end portion of the bed 10 is supported. Secured to the shafts 13 and 14 in bell crank arrangement with the arms 15 and 16 of the toggle levers are depending arms 18 connected by coiled springs 19 that normally hold said toggle levers upwardly buckled, as shown in Fig. 2. L-shaped arms 20 in bell crank arrangement with the arms 18 on the shaft 13 connect the paper clamp 12 to the said shaft for raising and lowering movements. Obviously, the springs 19 normally hold the toggle levers 15-16 with the paper clamp 12 pressed onto the top of the bed 10, and at which time said bed is supported on the legs 17 in horizontal position.

20 The following connections are provided for straightening the toggle levers 15-16 against the buckling action of the springs 19 to release the paper clamp 12 and lower the rear end of the bed 10, to wit: A vertical 25 movable lever-acting foot pedal 21 is pivoted to a fixed bracket 22 on a transverse rod 23 rigidly secured to the frame side members 9. Said foot pedal 21 is intermediately connected by a long link 24 attached to a 30 transverse rod 25 carried by the free rear ends of a pair of levers 26 pivoted on a shaft 13 and intermediately fulcrumed to the long arms 17 of the toggle levers. The parts thus far described are of standard and well 35 known construction and have been illustrated simply for the purpose of showing the aligning attachment in operative position.

A roll 27 containing four strips or webs of paper is mounted on a shaft 28 removably 40 journaled in open seats 29 formed in the intermediate portions of a pair of hanger bars 30, the ends of which are pivoted on a cross shaft 31 mounted in a pair of side plates 32 detachably secured to the frame top member 8. The lower ends of the hanger bars 30 are connected by a cross tie-rod 33. These 45 hanger bars 30 support the roll 27 for vertical swinging movement longitudinally of the machine. The roll 27, of course, may contain any desired number of webs and the 50 number of webs depends on the number of copies desired. The webs of paper forming the roll 27 have pairs of longitudinally spaced holes 34 punched therein. Said holes 55 of each pair are transversely spaced. The space between the longitudinally spaced pairs of holes 34 will contain printed forms to be filled in with a typewriter or autographing machine, not shown. Such a machine will be mounted on the frame top member 8 for co-operation with the flat bed or platen 10 on which the forms will rest. The 60 several webs of paper comprising the roll 27, as they are unwound therefrom, extend upward over the shaft 31 that acts as a guide

therefor and forward under the paper clamp 12 and lie on the bed 10 with one set of forms in position to be filled in by a typewriter or other machine. The clamp 12 holds the free ends of the paper webs pressed 70 onto the bed 10. By reference to Fig. 2 it will be noted that the outer web of the roll 27 is drawn taut and the other webs have considerable slack so that the several webs may be adjusted both longitudinally and 75 transversely in respect to each other to keep the same properly aligned.

As the forms are filled in, the operator depresses the foot pedal 23 to release the clamp 12 and grasps the paper webs under 80 said clamp and draws the same forward until the completed set of forms are entirely forward of the clamp 12 and then releases said clamp to hold the next set of forms on the bed 10, and tears off the completed set of forms, using said paper clamp as a tearing blade.

At the time the operator depresses the foot pedal 23 to release the clamp 12 the rear end portion of the bed 10 is lowered to 90 release the same from the webs of paper to permit the same to be freely drawn forward by the operator. In drawing the paper webs forward over the bed 10 the pull on the outer web, which is taut, will swing the roll 95 27 and hanger bars 30 slightly forward and when this movement of said webs is stopped, and the forward ends of the webs held by the clamp 12, said roll and bars will swing 100 rearward to normal position, thus drawing the outer web rearward to take up any slack therein and hold the same taut.

Referring now in detail to the aligning attachment, there is mounted on the frame top member 8, just forward of the shaft 31, 105 upper and lower transverse vertically spaced flat bars 35 and 36, respectively, between which the webs of paper are inserted with freedom to move as they are pulled forward over the bed 10.

A pair of headed aligning pins 37 are mounted in bore-like seats in the top bar 35 with freedom for vertical movement, and their lower ends project into the open notches 38 formed in the front longitudinal edge portion of the bar 36. These aligning pins 37 are yieldingly held projected between the bars 35 and 36 and into the notches 38 by a flat spring 39 intermediately secured to the top of the bar 35 with their free end portions resting on the heads of said pins. Said aligning pins 37 have the same transverse spacing as the holes 34 and are of such size as to freely enter said holes. During the forward movement of the paper webs on the bed 10, the lower ends of the aligning pins 37 rest directly on the uppermost paper web, and, when the next pair of holes 34 is brought into alignment with said pins, said pins are projected therein by the 115 120 125 130

spring 39 and stop further forward movement of the paper webs and position the filled in set of forms in their proper relation to the front edge of the clamp 12 to be torn off at this point. At this same time the next set of forms is properly positioned on the bed 10 for the writing machine.

10 The pins 37, by successively entering each pair of holes 34, keep the several strips of paper properly aligned both longitudinally and transversely and prevent the forms of each set from being pulled out of proper registration when the filled in set of forms is being torn off at the clamping bar.

15 To automatically lift the aligning pins 37 from the engaged pair of holes 34 simultaneously with the lifting of the clamp 12 to release the paper webs so that they may be pulled forward, there is provided, pin 20 ejectors in the form of a pair of tapered radial studs 40 axially aligned with said pins and having hubs 41 rockably mounted on a transverse shaft 42. This shaft 42 has its ends rigidly secured to bearing blocks 44 25 mounted in open seats 45 in the end plates 32 for vertical sliding movement which holds said shaft from turning. To raise the shaft 42 to project the ejecting studs 40 into the notches 38 and respective holes 34 and lift 30 the aligning pins 37 from said holes simultaneously with the lifting of the clamp 12 to release the paper webs, there is provided a bail-like lever 46 connected to the link 24 by a horizontal arm 47. The arms of this 35 lever 46 are intermediately fulcrumed at 48 to the side plates 32 and the short or free ends thereof are bifurcated and engage reduced portions 49 on the shaft 42. The intermediate portion of the bail-like lever 46 40 extends through a longitudinal slot 50 in the arm 47, and which arm is frictionally clamped to the link 24.

45 Mounted on the shaft 42, outward of the hubs 41, are fixed collars 51 having a stop shoulder 52 arranged to be engaged by a stop shoulder 53 on the hubs 41. Coiled springs 54, encircling the shaft 42, have one of their ends anchored to said shaft and their other ends anchored to the inner faces 50 of the hubs 41. The co-operating stop shoulders 52 and 53 are arranged to position the hubs 41 with the ejector studs 40 axially aligned with the aligning pins 37 and are yieldingly held in this position by the 55 springs 54. The co-operating stop shoulders 52 and 53 are so arranged that the ejector studs 40 are free to rock forward during the pull of the paper webs over the bed 10, as indicated by broken lines in Fig. 6. A cross tie bar 55 connects the side plates 32, forward of the bar 36, and its upper face is in the same plane as the top of said bar and the paper webs rest thereon.

60 The above described attachment may be 65 very quickly attached to the machine sim-

ply by securing the side plates 32 to the frame top member 8 and arm 50 to the link 24.

Operation.

70

The operation of the machine and attachment may be briefly described as follows:

At the time a set of forms is filled in by a writing machine, the operator depresses the foot pedal 21 to raise the paper clamp 12 and 75 at the same time the shaft 42 is automatically lifted by the connections 24—47—46 which projects the ejecting studs 40 into the aligned pair of holes 34 and lifts the aligning pins 37 therefrom. With the paper webs thus released, the operator pulls said webs forward by grasping the free ends thereof under the raised paper clamp 12. This forward movement of the paper webs rocks the ejector studs 40 in the open notches 38 and out of 80 the engaged pair of holes 34 against the tension of the springs 54, as shown in Fig. 6 by means of broken lines. As the ejector studs 40 are thus rocked forward the respective pair of holes 34 is moved out of alignment 85 with said pins and said pins are gradually lowered by said studs onto the top of the paper webs. During the forward movement of the paper webs the spring-pressed pins 37 rest thereon. When the next set of holes 34 90 is brought into alignment with the pins 37, said pins are projected therein to align the several paper webs both longitudinally and transversely. At the time the pins 37 enter a pair of holes 34, further movement of the 95 paper webs is stopped by said pins and the operator releases the foot pedal 21 which returns the paper clamp 12 to normal position in which it clamps the paper webs onto the bed 10, and at the same time the shaft 42 is 100 lowered by the connections 24—47—46 and the springs 54 return the ejector studs 40 to normal position in which they are aligned with the pins 37.

105 After the paper clamp 12 is released the operator tears the completed set of forms from the paper webs, using the clamp 12 as a tearing edge. It will thus be seen that each set of forms is properly and accurately aligned both longitudinally and transversely 110 at the time the same is drawn onto the bed 10 and positioned for the writing apparatus.

115 What I claim is:

1. In a typewriter adapted to use a work web having longitudinally spaced holes and 120 arranged to be fed through the machine, the combination with an aligning pin arranged to bear on the web of paper and be successively projected into said holes during the feeding action of said web, of an ejector for 125 said pin arranged to enter said holes during its ejecting action and to be moved out of said holes by said web, during its feeding action.

2. In a typewriter adapted to use a work 130

4

web having longitudinally spaced holes and arranged to be fed through the machine, the combination with an aligning pin arranged to be automatically projected successively into said holes during the feeding action of said web, of an ejector for said pin arranged to enter said holes during its ejecting action and to be moved out of said holes by said web during its feeding action, to release 10 said pin.

3. The structure defined in claim 2 in further combination with automatic means for repositioning the ejector in respect to the aligning pin.

15 4. In a typewriter adapted to use a work web having longitudinally spaced holes and arranged to be fed through the machine, a clamp for the web, and an actuated member for releasing the clamp, the combination 20 with an aligning pin arranged to be automatically projected successively into said holes during the feeding action of said web, of an ejector for said pin automatically operated by said member and arranged to enter 25 said holes during the ejecting action and to be moved out of said holes, by said web during its feeding action, to release said pin.

5. In a typewriter adapted to use a work web having longitudinally spaced holes and 30 arranged to be fed through the machine, a clamp for the web, and an actuated member for releasing the clamp, the combination with a yieldingly held aligning pin arranged to bear on said web as the same is fed through 35 the machine and be projected successively into said holes, of an ejector for said pin automatically operated by said member and arranged to enter said holes and eject said pin and to be moved out of the holes by said 40 web, during its feeding action, to release said pin onto the web, and automatic means for repositioning the ejector in respect to the aligning pin.

45 6. In a typewriter adapted to use a work web having longitudinally spaced holes and arranged to be fed through the machine, the combination with an aligning pin, an ejector for the aligning pin, said pin and ejector being aligned and on opposite sides of the web 50 of paper for movement toward each other, said aligning pin being arranged to successively enter said holes during the feeding action of said web, said ejector being arranged to enter said holes during its ejecting 55 action and to be moved out of said holes by said web during its feeding action.

60 7. In a typewriter adapted to use a work web having longitudinally spaced holes and arranged to be fed through the machine, a clamp for the web, and an actuated member for releasing the clamp the combination with an aligning pin arranged to be automatically projected successively into said holes during the feeding action of said web, of an 65 ejector for said pin mounted for axial move-

ment in respect to said pin and for rocking movement in respect to the direction of the feeding action of said web, yielding means normally holding the ejector axially aligned with said pin, and automatic means for 70 operating the ejector in timed relation to said member, said ejector being arranged to enter said holes during its ejecting action and to be rocked out of said holes against said yielding means by said web, during its 75 feeding action, to release said pin.

8. In a typewriter having a bed, a co-operating web clamp and manually operated connections for releasing said clamp, and adapted to use a work web having longitudinally spaced holes arranged to be alternately fed over said bed and held by said clamp, the combination with a yieldingly held aligning pin arranged to bear on said web as the same is fed over the bed and be projected successively into said holes, of an ejector for said pins, operated by said connections in timed relation with the paper clamp and arranged to enter said holes and eject said pin and be moved out of said 90 holes by said web, during its feeding action, to release said pin onto said web, and automatic means for repositioning the ejector in respect to the aligning pin.

9. In a typewriter having a bed, a co-operating web clamp and manually operated connections for releasing said clamp, and adapted to use a work web having longitudinally spaced holes arranged to be alternately fed over said bed and held by said clamp, the combination with a yieldingly held aligning pin arranged to bear on said web as the same is fed over the bed and be projected successively into said holes, of a radially movable shaft, an ejector mounted on the 100 shaft for rocking movement in the direction of the feeding action of said web, a spring normally holding said ejector axially aligned with said pin and against said rocking movement, and means actuated by said connections for moving said shaft radially to cause said ejector to enter said holes and eject said pin in timed relation to the releasing of the paper clamp, said ejector being rocked out of said holes by said web, during its feeding 105 action, to release said pin onto said web.

10. In a typewriter having a bed, a co-operating web clamp and manually operated connections for releasing said clamp, and adapted to use a work web having longitudinally spaced holes arranged to be alternately fed over said bed and held by said clamp, the combination with an upper bar and a lower bar vertically spaced, between which said web is fed, said lower bar having a notch, of a yieldingly pressed aligning pin mounted in said upper bar over said notch and arranged to bear on said web and be projected successively into said holes and notch, a radially movable shaft, an ejector 125

mounted on said shaft for rocking movement in the direction of the feeding action of said web, a spring normally holding said ejector axially aligned with said pin and against said rocking movement, and a lever actuated by said connections, during their movements to release the paper clamp, for moving said shaft radially to cause said ejector to enter said holes and eject said pin, said ejector being rocked out of said holes by said web, during its feeding action, to release said pin onto said web.

11. The structure defined in claim 8 in further combination with automatic means for drawing the web taut from the web clamp.

12. In a typewriter having a bed and a co-operating web clamp, the combination with a hanger, of a work web in a roll mounted on said hanger and arranged to be alternately fed over said bed and held by said clamp, said hanger being suspended for swinging movement in the direction of travel of the web over the bed to the web clamp.

13. The structure defined in claim 12 in which said web has longitudinally spaced holes, and in further combination with an aligning pin arranged to be automatically projected successively in said holes, and an ejector for said pins.

14. In a typewriter having a bed and a co-operating web clamp, manually operated connections for releasing said clamp, and a roll comprising a plurality of webs having longitudinally spaced pairs of holes arranged to be alternately fed over said bed and held by said clamp, the combination with an upper bar and a lower bar vertically spaced, said lower bar having a pair of notches, a pair of spring-pressed aligning

pins mounted in the upper bar and arranged to bear on said web and be projected successively into said holes and notches, of a radially movable shaft, an ejector mounted on said shaft for rocking movement in the direction of the feeding action of said web, a spring normally holding said ejector axially aligned with said pin and against said rocking movement, and a lever actuated by said connections, during their movements to release the paper clamp, for moving said shaft radially to cause said ejector to enter said holes and eject said pin, said ejector being rocked out of said holes by said web, during its feeding action, to release said pin onto said web.

15. The structure defined in claim 14 in further combination with a hanger for the roll of paper suspended on the machine for swinging movement in the direction of travel of the paper over the bed to the web clamp.

16. The structure defined in claim 1 in further combination with automatic means for repositioning the ejector in respect to the aligning pin.

17. In a typewriter adapted to use a work web having longitudinally spaced holes and arranged to be fed through the machine, the combination with an aligning pin and an ejector therefor, said pin and ejector being aligned with the web of paper extending therebetween, said aligning pin being arranged to be successively projected into said holes during the feeding action of said web, said ejector being arranged to enter said holes during its ejecting action and be automatically moved out of said holes by a movement in the direction of the feeding action of said web.

In testimony whereof I affix my signature.
JOSEPH RAYMOND YOUNG.
